UNITED STATES PATENT OFFICE.

HENRY ROTTENBURG, OF CAMBRIDGE, ENGLAND.

PUTTEE.

1,216,366.

Specification of Letters Patent. Patented Feb. 20, 1917.

Application filed November 10, 1916. Serial No. 130,605.

To all whom it may concern:

Be it known that I, HENRY ROTTENBURG, a subject of the King of Great Britain, and residing at 5 Adams road, Cambridge, England, have invented certain new and useful Improvements in Puttees, of which the following is a specification.

The present invention has for its object to provide a puttee which will be easier to 10 put on and will fit better than puttees as usually made, while it will also allow for a certain amount of expansion or accommodation in case the leg swells or the material of which the puttee is made shrinks. The 15 puttee is composed of a number of overlapping strips of material sewn or otherwise secured together along a middle line, and adapted to be lapped around the leg alternately from one side and the other in such 20 a way as to give an overlapping effect similar to that obtained with a straight puttee which is crossed at each turn. As each end of a strip is lapped over the preceding ends in turn the result is that all of the overlapping 25 ends are held in position, and they may hold sufficiently without any other means of securing them. A lace passing around hooks on the strips of material, or any other convenient device may be used for 30 holding the flaps in their proper positions more securely if desired.

The invention is illustrated in the accompanying drawings, wherein:—

Figure 1 shows a puttee laid out flat. 35 Fig. 2 shows a section on the line A—B of Fig. 1, indicating in dotted lines a portion of the leg to which the puttee is to be applied.

Fig. 3 is a corresponding view to Fig. 1, 40 but showing the initial stages of applying the puttee to the leg.

Fig. 4 shows the puttee as finally applied.

The puttee shown in Fig. 1 is made up of five strips, lettered C—D, E—F, G—H, 45 J—K and L—M. Each succeeding strip partially overlaps the preceding one as is shown, and the middle portions of the strips are connected together where they overlap, preferably along the line A—B in Fig. 1, 50 by sewing the strips one to another, or by sewing them all to a tape or the like extending along the said line, or in any other convenient way, leaving the ends of the strips free. At the middle of the strip 55 L—M on the inside thereof, a tab N may be attached, formed with a buttonhole to

engage with a button secured to the breeches, as is usual when leggings are worn, or a tape R may be used for tying the puttee at the top upon the calf of the leg. For fastening the puttee at the top a tape O may be secured to one end of the topmost strip for use in the well known way, or any other means of securely fastening the uppermost strip L—M of the puttee may be provided. 60 65

In applying the puttee to the leg, its middle line is laid along the calf at the back, while the ends of the separate strips are lapped around the front alternately. For example, in Fig. 3 the end C of the loose 70 strip has been wrapped around the ankle, and then the other end D of the same strip has been lapped over the end C. Next, the end E of the succeeding strip will be lapped over, then the end F, and so on for each succeeding strip up to the top. The tape O may then be wrapped around the top strip as indicated in Fig. 4, in a manner analogous to that in which the tape is used on a straight or spiral puttee. 75 80

The puttee applied in the manner above described will hold quite well and the overlapping flaps or ends of the strips will not pull out with ordinary use, but if the puttee were caught by anything the flaps might be 85 opened out somewhat; in order to make this impossible the overlapping flaps may be laced as indicated, if they are provided with eyelets or with hooks P such as are used on boots, and if a lace Q is passed around the 90 hooks, and tied in any suitable way, for instance by passing it from the bottom over the succeeding hooks upwardly and then back again to the bottom hook. A single lace might also be used fastened for instance to the end C of the first strip, carried over the hooks on the succeeding strips, and then carried from the hook on the last flap M around the top of the leg, and tucked in with the tape O, or otherwise fastened. 95

In order to facilitate the putting on of the puttee, if no button is provided on the breeches the tape R may be used, this tape being tied around the top of the calf of the leg before beginning to lap the ends of the strips around the front of the leg. Both the tab N and tape R may be provided as shown so that either can be used as is most convenient. 100 105

In the case of puttees which are to be 110 worn for riding, the part of the puttee which comes in contact with the horse or the

saddle can be faced with leather or other hard-wearing material if required.

The topmost strip L—M may be straight like the others, but it is preferably shaped 5 as shown so that its upper edge may lie approximately horizontally, or straight around the leg when applied thereto. The ends of the strips may be rectangular or their corners may be rounded as shown. It will be 10 obvious however that the strips might be made of any other desired shape, and they are not necessarily of equal width nor are their upper and lower edges necessarily parallel. Although a puttee with five or six 15 strips has been found convenient, yet it will be apparent that a puttee could be made on the same principle with any desired number of strips secured together for use in the manner hereinbefore described.

20 The tapes R for use in holding the puttees in position while the ends of the strips are lapped over, may be colored differently for the right and for the left legs so as to facilitate distinguishing between the puttees intended for each leg. Although the 25 puttees are shown as being closed and laced at the front of the leg in Fig. 4, yet they may be closed and laced at the side or at the back if preferred, without any alteration 30 in the principle on which the puttee is made up.

Having thus described my invention, what I claim as new and desire to secure by Letters Patent is:—

35 1. A puttee consisting of a number of strips of flexible material arranged successively to overlap one another along their edges, means securing said strips together in the middle parts thereof where they overlap, in such a manner as to leave the ends 40 of the strips free to be lapped around the leg successively in overlapping positions,

and means for securing the strips in the successively overlapped positions when applied to the leg.

45 2. A puttee consisting of a number of strips of flexible material arranged successively to overlap one another along their edges, means securing said strips together in the middle parts thereof where they overlap, in such a manner as to leave the ends of the strips free to be lapped around the leg successively in overlapping positions, and means for securing the uppermost strip with its ends overlapping around 50 the leg, whereby also the succession of strips each with its end overlapped by the last is held closed around the leg.

55 3. A puttee consisting of a number of strips of flexible material arranged successively to overlap one another along their edges, means securing said strips together in the middle parts thereof where they overlap, in such a manner as to leave the ends of the strips free to be lapped around the 60 leg successively in overlapping positions, a plurality of hooks applied to the respective strips on their outer faces near to the ends thereof, and means for lacing the strips together around the said hooks.

65 4. A puttee consisting of a number of strips of flexible material arranged successively to overlap one another along their edges, means securing said strips together in the middle parts thereof where they overlap, in such a manner as to leave the ends of the strips free to be lapped around the leg successively in overlapping positions, a 70 tape adapted to bind the uppermost overlapped strip around the leg, and means for lacing together the overlapped ends of the strips when applied to the leg.

75 HENRY ROTTENBURG.
